Inventor,

William J. O'Sullivan

UNITED STATES PATENT OFFICE.

WILLIAM J. O'SULLIVAN, OF NORFOLK, VIRGINIA.

STRUCTURAL ANGLE BAR.

Application filed December 7, 1922. Serial No. 605,496.

To all whom it may concern:

Be it known that I, WILLIAM J. O'SULLIVAN, a citizen of the United States, residing at 529 Thirty-seventh Street, Norfolk, in the county of Norfolk, State of Virginia, have invented certain new and useful Improvements in Structural Angle Bars, of which the following is a specification, reference being had to the accompanying drawings.

The object of this invention is to provide structural angle bar which while having no greater over all dimensions nor greater cross sectional area than a similarly shaped structural angle bar as now made, will at the same time resist greater stresses.

This is accomplished by providing an angle bar whose center of gravity about an axis at right angles to one of its legs, the legs being at right angles to each other, is at a greater distance from the back of its other leg than in angle bars as now made.

In the accompanying drawings, Figure 1 is a cross-sectional view of a standard angle bar as now made in which A designates the angle bar, B its primary leg, C its secondary leg, $a-a$ an axis at right angles to its primary leg and passing through the center of gravity of the angle bar and α the distance of said axis $a-a$ from the back of the secondary leg C. The nominal dimension of the angle bar A are six (6) inches extreme width of primary leg, four (4) inches extreme width of secondary leg, and five-eighths ($\frac{5}{8}$) of one inch thickness of each leg B and C but its actual dimensions substantially are six and one-fourth ($6\frac{1}{4}$) inches extreme width of primary leg, four and one-fourth ($4\frac{1}{4}$) inches extreme width of secondary leg and five-eighths ($\frac{5}{8}$) of one inch thickness of each leg B and C.

Figure 2 is a cross-sectional view of an angle bar as I propose to make it, in which D designates the angle bar, E its primary leg, F its secondary leg, $b-b$ an axis at right angles to its primary leg and passing through the center of gravity of the angle bar E and y the distance of said center of gravity $b-b$ from the back of its secondary leg F. The over all dimensions and cross sectional area of the angle bar D are the same as those of the angle bar A but the thickness of its primary leg E is seventy-five hundredths (.75) of an inch and the thick-

ness of its secondary leg F is four hundred and twenty-four thousandths (.424) of an inch.

Figure 3 is a cross sectional view of a built-up structural section G composed of four angle bars A as shown in Figure 1 and a web plate H, all riveted together. The web plate H is one-half ($\frac{1}{2}$) inch by twelve (12) inches wide.

Figure 4 is a cross sectional view of a built-up structural section I, composed of four angle bars D, as shown in Figure 2 and a web plate H, all riveted together. The over-all dimensions and cross-sectional area of the built-up section I is the same as those of the built-up section G. The web plate is one-half ($\frac{1}{2}$) inch thick by twelve (12) inches wide, the same as used in the built-up section G.

All like letters in the various figures refer to identical parts.

To increase the strength of an angle bar about an axis $a-a$, without increasing its over all dimensions or its cross-sectional area, I effect in the rolling of the angle bar a redistribution of the metal composing an angle bar A as now rolled by decreasing uniformly the thickness of its secondary leg C and with the metal thus saved increasing uniformly the thickness of its primary leg B thus making what I call a thick-and-thin angle bar D, the primary leg E being the thick leg and the secondary leg F being the thin leg. The center of gravity distance α on the leg B of the angle bar A becomes increased to distance y on the leg E of the angle bar D which increase, up to a certain point, allows a greater stress to be safely imposed upon the angle bar acting in a direction in relation to its axis $b-b$.

To better explain this I will call attention to the derivation from the moment of inertia of the section modulus and the radius of gyration, both of which are used in determining the amount of stress that is to be allowed upon a structural part; the section modulus for parts subject to bending, as a beam, and the radius of gyration for parts subject to compression as a column or a strut, the least section modulus, which is the determining one, being the quotient of the moment of inertia divided by the distance from the center of gravity to the most dis-

tant edge or most remote fibre, and the radius of gyration being expressed as the square root of the number obtained by dividing the moment of inertia by the cross sectional area.

In Figure 1 the standard angle bar A has a cross sectional area of six and fourteen hundredths (6.14) square inches, a distance x of two and six hundredths (2.06) inches, a moment of inertia of twenty-three and twenty-nine hundredths (23.29) a least section modulus of five and fifty-six hundredths (5.56), and a radius of gyration of one and ninety-five hundredths (1.95), as calculated in inches about axis $a-a$.

In Figure 2 the thick-and-thin angle bar D as I propose to make it has a cross sectional area of six and fourteen hundredths (6.14) square inches the same as angle bar A, a distance y of two and thirty-nine hundredths (2.39) inches, a moment of inertia of twenty-five and two hundredths (25.02) a least section modulus of six and ninety-three hundredths (6.93) and a radius of gyration of two and two hundredths (2.02), as calculated in inches about axis $b-b$.

As the beam strength of a structural part increases directly as its least section modulus is increased, it is apparent from a comparison of the section moduli of the two angle bars A and D that although the over all dimensions and the cross sectional area of the angle bar D are the same as those of the angle bar A the beam strength of the angle bar D about its axis $b-b$ is twenty-four (24%) per cent greater than the beam strength of the angle bar A about its corresponding axis $a-a$.

Also, as the column or strut strength of a structural part increases when its radius of gyration is increased, it is apparent from a comparison of the radii of gyration of the two angle bars A and D that, although the over all dimensions and the cross sectional area of the angle bar D are the same as those of the angle bar A, the column or strut strength of the angle bar D about its axis $b-b$ is greater than the column or strut strength of the angle bar A about its corresponding axis $a-a$. Applying the well known column formula of $p=16000-70 1/r$ in which 1 is the column length in inches, r the radius of gyration as calculated in inches and p the allowed compressive stress per square inch of cross sectional area, it will be found that for a length of twenty feet (20'0'') the angle bar A will safely sustain the equivalent of a compressive load of forty-five thousand three hundred (45,300) pounds in relation to its axis $a-a$, while the angle bar D will safely sustain the equivalent of a compressive load of forty-seven thousand two hundred (47,200) pounds in relation to its corresponding axis

$b-b$, or four and two-tenths percent (4.2%) more than will the angle bar A.

In Figure 3 the built-up section G composed of the four angle bars A and the web plate H has a cross sectional area of thirty- 70 and fifty-six (30.56) hundredths square inches, distances x' of two and thirty-one hundredths (2.31) inches, a moment of inertia, of two hundred and fourteen and twenty-eight hundredths (214.28), a section 75 modulus of thirty-two and ninety-five hundredths (32.95) and a radius of gyration of two and sixty-five hundredths (2.65) as calculated in inches about axis $a'-a'$.

In Figure 4 the built up section I composed of four angle bars D has a cross sectional area of thirty and fifty-six hundredths (30.56) square inches, the same as the built-up section E, distances y' of two and sixty-four hundredths (2.64) inches, a 85 moment of inertia, of two hundred and seventy-five and forty hundredths (275.40) inches, a section modulus of forty-two and thirty-seven hundredths (42.37) as a radius of gyration of three (3.00) as calculated in 90 inches about axis $b'-b'$.

It is apparent from a comparison of the section moduli of the two built up sections G and I that, although the overall dimensions and the cross-sectional area of the section I are the same as those of the section G the beam strength of the section I about its axis $b'-b'$ is twenty-eight and five-tenths percent (28.5%) greater than the beam strength of the section E about its 100 corresponding axis $a'-a'$.

Also, it is apparent from a comparison of the radii of gyration of the two sections G and I that, although the overall dimensions and the cross sectional area of the section I are the same as those of the section G, the column or strut strength of the section I about its axis $b'-b'$ is greater than the column or strut strength of the section G about its corresponding axis $a'-a'$. 110 Applying the herein previously used column formula it will be found that for a length of thirty- feet (30'0'') the section G will safely sustain a compressive load of two hundred and eight thousand (208,000) 115 pounds in relation to its axis $a'-a'$ while the section I will safely sustain a compressive load of two hundred and forty-two thousand (242,000) pounds in relation to its corresponding axis $b'-b'$, or eleven per- 120 cent (11%) more than will the section G.

This invention consists essentially in producing a structural angle bar whose center of gravity on an axis at right angles to one of its legs is more distant from the back 125 of its other leg, this distance hereinbefore being called distance x and distance y , than on any angle bar now made, each of whose legs is of uniform thickness, and whose over all dimensions and cross-sectional area are 130

the same as on this newly invented angle bar.

No structural angle bar having legs of uniform thickness that I am aware of is made whose center of gravity distance x as hereinbefore described is greater than thirty-eight percent (38%) of the extreme width of the leg for which this center of gravity distance x is calculated, and no structural angle bar, having legs of uniform thickness that I am aware of is made, the extreme width of one of whose legs being not less than sixty-seven percent (67%) of the extreme width of its other leg, whose center of gravity distance x on said other leg is greater than thirty-four and five-tenths percent (34.5%) of the extreme width of the leg for which this center of gravity distance x is calculated.

20 What I claim is:

1. A structural angle bar neither of whose legs is less than two (2'') inches in extreme width, having each leg substantially of uni-

form thickness except for edge roundings and angle fillets, one leg being thicker than 25 the other leg.

2. A structural angle bar whose legs being each of substantially uniform thickness except for edge roundings and angle fillets, the center of gravity of which angle bar on 30 an axis at right angles to one of its legs is situate not less than thirty-eight (38%) percent of the extreme width of said leg from the back of its other leg.

3. A structural angle bar whose legs being each of substantially uniform thickness except for edge roundings and angle fillets, the extreme width of one leg being not less than sixty-seven percent (67%) of the extreme width of the other leg the center 40 of gravity of which angle bar on an axis at right angles to one of its legs is situate not less than thirty-four and five-tenths percent (34.5%) of the extreme width of said leg from the back of its other leg.

WILLIAM J. O'SULLIVAN.
